CLAIM

The ornamental design for a low profile antenna for a vehicle, as shown and described.

DESCRIPTION

FIG. 1 is a front perspective view of a low profile antenna for a vehicle in accordance with my new design;

FIG. 2 is a top plan view of the low profile antenna for a vehicle in accordance with my new design;

FIG. 3 is a bottom plan view of the low profile antenna for a vehicle in accordance with my new design;

FIG. 4 is a front elevational view of the low profile antenna for a vehicle in accordance with my new design;

FIG. 5 is a left side elevational view of the low profile antenna for a vehicle in accordance with my new design; and,

FIG. 6 is a right side elevational view of the low profile antenna for a vehicle in accordance with my new design. The rear elevational view is omitted because the rear elevational view is a mirror image of the front elevational view shown in FIG. 4.

The broken line showing of environmental structure in the drawings forms no part of the claimed design. The portions within the broken lines form no part of the claimed design.
